DOOR ROTOR LOCK ASSEMBLY OR SIMILAR ARTICLE

Lyle M. Northrup, New Hampton, Iowa, assignor to
Lynor Engineering, Inc.

Filed July 17, 1973, Ser. No. 380,103

Term of patent 7 years

Int. Cl. D8—07, 06

U.S. Cl. D8—109

FIG. 1 is a front elevational view of the door rotor lock assembly or similar article showing my new design;

FIG. 2 is a side elevational view from the right of FIG. 1;

FIG. 3 is a side elevational view from the left of FIG. 1;

FIG. 4 is a rear elevational view; and

FIG. 5 is a top plan view.

I claim:

The ornamental design for a door rotor lock assembly or similar article, substantially as shown.
